Hazard & Miller

UNITED STATES PATENT OFFICE.

ENOS E. SUTHERLAND, OF LOS ANGELES, CALIFORNIA.

COLLAPSIBLE CRATE.

Application filed April 18, 1922. Serial No. 555,396.

To all whom it may concern:

Be it known that I, ENOS E. SUTHERLAND, a citizen of the United States, residing at Los Angeles, in the county of Los Angeles 5 and State of California, have invented new and useful Improvements in Collapsible Crates, of which the following is a specification.

This invention relates to collapsible receptacles and more particularly to that type of receptacle disclosed in my allowed application Serial No. 457,162, filed March 31, 1921, to which reference is made for a full description of the receptacle.

It is an object of my present invention to improve the means for locking the basket or receptacle in its erected position independently of the fact whether the cover is applied or not.

One embodiment of the invention is herein described and illustrated in the accompanying drawings, in which

Figure 1 is a perspective of the crate in assembled position showing the fastening means as disconnected and open.

Fig. 2 is a plan of the receptacle showing the fastening means in closed and secured position.

Fig. 3 is a perspective of a form of top closure for the receptacle.

Fig. 4 is a perspective of my improved fastening means.

Fig. 5 is a perspective of a key cooperative with the fastening means to secure the same locked.

The crate shown in Fig. 1 is preferably a rectangular structure including opposite side walls 1 and opposite side walls 2 arranged at right angles thereto when the crate is unfolded. Each of the side walls preferably comprises upper and lower cross members 3 connected by vertical slats 4 transversely spaced as shown at 5 in order to lighten the construction, and as a consequence make an inexpensive structure and one which permits of ready viewing of the articles contained within the same.

Link connections are provided between adjacent side walls, and these links are preferably arranged at the upper and lower edges of the meeting ends of adjacent side walls. Each of the links comprises a wire loop 6 having opposite portions thereof pivoted to the respective adjacent side walls

as by receiving said opposite portions of the 55 loop through bearings 7 formed between cross members 3 and slats 4.

As will be readily understood by reference to Figs. 1 and 2, the loops forming the links are thus adapted to extend across the 60 corners formed by adjacent side walls with the ends of the loops pivoted to the respective adjacent side walls, and the upper and lower portions of the loops extending angularly across the corners above and below 65 cross members 3. The construction, as thus described, permits of ready collapsing of the crate by simply folding one pair of adjacent side walls 1 and 2 upon the opposite 70 corners formed by adjacent side walls 1 and 2, it being noted that the link connections between the adjacent side walls permit of sufficient relative movement of said side walls to allow such collapsing.

End members are arranged within the 75 crate, as thus constructed, and are adapted to hold the same against collapse. Each of these end members may comprise a frame consisting of cross bars 10 and transversely spaced slats 11 fixed thereon. One of the 80 end members is adapted to be inserted in the unfolded crate so as to rest upon the tops of the lower link connections between the side walls, and if desired, a similar closure plate may rest upon the top of the 85 crate in order to close the upper end of the same. It will thus be noted that when the closure plates are in position the crate will be held in extended position, and that when the closure plates are removed the crate may 90 be readily collapsed.

In my present invention the erected receptacle is conveniently and readily locked in assembled position by means which also forms a convenient handle by which the receptacle may be transported from place to place.

The fastening means preferably consists of a pair of bail like members 15, the shanks of each of which converge upwardly to a helix 16 forming a handle portion, while the lower end of the shanks 15 of each bail diverge and are provided with eyes 17 pivoted upon the diagonal link or loop members 6 at the upper end of the receptacle. The length of the bails are such that when the two bails are swung with their helical portions 16 into meeting position as shown 100 105

in Figs. 2 and 4, the coils of the helices intermesh, and through the center opening within the helices there may be passed a suitable key member 18. This key member 5 may be made of flat wire and has the generally straight shank with an intermediate hump or bow 19 designed to be intermeshed with the coils of the coordinate helices. This prevents the helices 16 from separating. 10 From the above it will be seen that I have provided an extremely simple form of fastening means for securing the erected elements of the receptacle, and further to provide a fastening means which is serviceable as a handle for carrying the receptacle.

In Fig. 3, it will be seen that the corners of one of the side members 10 are diagonally cut away as at 13 to provide for the insertion of the top forming structure in the top 20 of the erected receptacle.

Various changes and modifications may be made without departing from the spirit of the invention as claimed.

What is claimed is:

25 1. The combination with a collapsible receptacle having hinge forming members at the corners of the side walls, of bail like means pivoted upon said members and

adapted to be moved into interengaging position.

2. The combination with a collapsible receptacle having hinge forming members at the corners of the side walls, of bail like means pivoted upon said members and adapted to be moved into interengaging position, said members being provided with portions forming handles whereby the receptacle may be carried.

3. The combination with a collapsible receptacle having hinge forming members at the corners of the side walls, of bail like means pivoted upon said members and adapted to be moved into interengaging position, said bails having helical intermediate portions intermeshing when they are brought into co-axial relation.

4. The combination with a collapsible receptacle having hinge forming members at the corners of the side walls, of bail like means pivoted upon said members and adapted to be moved into interengaging position, and a key like member for securing the interengaged portions of the bails.

In testimony whereof I have signed my name to this specification.

E. E. SUTHERLAND.
